UNITED STATES PATENT OFFICE.

MORRIS S. WRIGHT, OF WORCESTER, MASSACHUSETTS, ASSIGNOR TO M. S. WRIGHT COMPANY, OF WORCESTER, MASSACHUSETTS, A CORPORATION OF MASSACHUSETTS.

VACUUM-CLEANER.

1,233,948.

Specification of Letters Patent. Patented July 17, 1917.

Application filed June 1, 1911. Serial No. 630,727.

To all whom it may concern:

Be it known that I, MORRIS S. WRIGHT, a citizen of the United States, residing at Worcester, in the county of Worcester and

5 State of Massachusetts, have invented certain new and useful Improvements in Vacuum-Cleaners, of which the following is a specification, reference being had thereto in to the accompanying drawing.

10 This invention relates to certain improvements in vacuum cleaners and though susceptible of a variety of adaptations is more especially designed for use in homes for the cleansing of carpets and the like, and

15 to this end is portable in character.

The present invention is of the same general character illustrated in my copending application filed of even date herewith, bearing Serial No. 630,726.

20 Embodied in the present invention is a novel form of vacuum creating means adapted for drawing into the apparatus dust laden air or the like, and an improved type of operating mechanism for the 25 vacuum creating means, thus producing more uniform suction, and rendering the vacuum creating means more powerful in operation.

To the above end, the invention includes 30 a novel form of motor drive for the apparatus, supported by the latter, and arranged so as to take up a minimum amount of space.

Also the invention includes a movable 35 operating brush or the like at the inlet end of the apparatus, and a novel form of operating mechanism therefor.

The invention also embraces a novel and common drive for both said operating device 40 at the inlet end of the apparatus and the vacuum creating means.

Still further improvements, and many novel details in the construction and arrangement of the various parts of the apparatus, will be further alluded to hereinafter in the detail description, and for a clear understanding thereof attention is directed to the accompanying drawings, which form a part hereof, and wherein convenient and 45 satisfactory embodiments of the invention are disclosed for the purpose of illustration.

In the drawings:

Figure 1 is a side elevation of the machine,

55

Fig. 2 is a longitudinal section,

Fig. 3 is a transverse section substantially on the line 3—3 of Fig. 2,

Fig. 4 is a transverse section substantially on the line 4—4 of Fig. 2,

60

Fig. 5 is an enlarged detail view partly in section of one form of nozzle attachment,

Fig. 6 is a side elevation disclosing another form of nozzle head attachment provided with a rotary brush and drive connection therefor,

65

Fig. 7 is a transverse section showing the application of the rotary brush or operating tool to the head.

70

Fig. 8 is a sectional view of a modified form of construction.

With more particular reference to the drawings, wherein like reference numerals designate corresponding parts throughout the several views, a suitable casing is provided including a bottom wall 1, a rear wall 2, a top wall 3. A transverse partition wall 4 arranged intermediate the ends of the casing divides the latter into two chambers, the one 5, comprising a vacuum chamber or dust receiving chamber, and the other 6, a motor chamber, the top wall 3 terminating adjacent the partition wall 4, whereby to provide an enlarged space for the motor mechanism

85

to be hereinafter described. The supporting wheel for the mechanism, indicated by the reference numeral 7 projects through an aperture 8 in the bottom 1 of the casing and is supported in bearings 9 projecting

90

through said bottom wall. By this construction, the wheel is practically concealed from view and offers no obstruction beyond the sides of the apparatus. Also the wheel being positioned substantially midway of

95

the sides of the casing the same constitutes with the nozzle member at the forward end of the apparatus a three point suspension permitting the nozzle of the apparatus to closely engage the floor even though the latter be slightly inclined.

Positioned within the chamber 6 is a suitable motor 10, an electric motor, and projecting from one side of the motor is a suit-

able drive shaft 10^a having a worm 10^b adapted to engage a gear wheel 10^c positioned within a suitable casing, which for convenience is formed in two sections 10^d and 10^e secured as by removable bolts 10^f, the arrangement being such as to permit ready access and removal of the parts within the casing by simply removing the upper section thereof. Projecting from opposite sides of the casing and secured to the gear wheel 10^c are rotatable drive shafts 11 having oppositely extending crank projections 12 adapted to support stub shafts 13. Loosely sleeved upon the stub shafts 13 are upright pitman rods 14, there being one of these rods and connections for each pump. Supported upon the top wall 3 are suitable pumps, two of which being shown for the purpose of illustration, and designed to be alternately acting. The pumps include each a bottom stationary wall 15 resting upon the top 3 and secured thereto in any desired manner, an upper wall 16 hingedly connected at its forward end at 16^a to the forward end of the lower wall 15 and having flexible connecting side walls 17 and rear end walls 18. The lower wall 15 has an opening 19 arranged to register with an opening 20 in the top wall 3 of the casing, and a suitable valve 21, preferably a flat valve, is designed to operate over the opening 20, the same being preferably connected at one end to the top 3 and adapted to open and close at its free end according to the action of the pump. The pump also has a valve controlled opening 22 in its movable wall 16, the said opening leading to the outside of the pump. Projecting rearwardly from the rear end of the movable walls 16 are metallic bracket members 23, there preferably being a pair for each wall 16 and adapted to be positioned between the brackets of each pair are the upper ends of the connecting rods 14. A suitable pin or the like 24 passing through registering apertures in the brackets 23 and the connecting rod 14 serves to form a loose bearing for the upper end of said rod.

A push handle 25 is provided, the same having a bifurcated lower end, the furcations 26 of which pass over opposite sides of the casing and are pivotally secured to the latter as by bolts 27. Means are provided for normally holding the handle in an upright position when the machine is in operation, the same including preferably a wire rod 28 having bent terminals 29. This rod which may be termed a bracket support, is pivotally connected to the casing as by bearings 30 and stops 31 on the casing, serve to limit the inward and upward swinging movement of the arms 29, which said arms when in this position constitute substantial and rigid supports for the arms 26 of the push handle. It will be seen that upon ex-

erting downward pressure upon the handle 25, which is resisted by the arms 29, the apparatus may be tilted at the forward edge thereof, whereby to run over the edges of rugs and the like. Now should it be desired to operate the apparatus beneath articles of furniture, such as a bed, it is sometimes found that the handle when in its normal position will constitute a substantial projection above the top of the apparatus and interfere with this operation, in which event the arms 29 are swung outwardly and downwardly whereby to release the handle and permit the same to lower as is obvious. A filtering bag 32 overlies the opening at the front end of the vacuum chamber 5 and is supported on a removable frame 33, whereby the same may be emptied as desired.

It is contemplated by the present invention to provide various forms of inlet heads or nozzle parts for the apparatus, permitting the same to be interchangeable as desired, according to the use to which the apparatus is put.

In Figs. 1 and 2 it will be observed that the head or nozzle part designated by the reference numeral 34 has an opening 35 in the mouth thereof, which mouth is adapted to engage over the surface to be cleaned, and which opening 35 connects with a transversely extending opening 36 communicating with the open end of the filtering bag 32. A buffer 37 is connected to the outer surface of the nozzle 34 adjacent the mouth thereof. Preferably springs 39 yieldably engage parts 40 of the casing, when the nozzle part is in position. Interposed between the nozzle 34 and the frame 33 is a suitable washer or packing 40^a, which is of a size to project beyond the frame 33 and overlie the outer edge of the walls of the casing, whereby when the nozzle is in position an air tight joint is formed at this point. The nozzle is preferably held in position as by leaf springs 41 secured at one end to the nozzle 34 and free at their opposite end and adapted to be engaged by a locking bracket 42 substantially U-shaped, pivotally connected to the casing at 43, whereby the same may be swung into and out of engagement with the spring arms 41, which latter may if desired, be provided with a bent part 43^a constituting a receiving recess. A stop 44 limits the downward movement of the locking arm 42.

That form of head illustrated in Fig. 5 may be substituted as desired, and in this figure the nozzle part 45 has an opening transversely thereof as at 46, which opening communicates with the open end of the filtering bag, and secured to the wall of the nozzle adjacent said opening is a hose or piping 47 or the like, which may be of a character and length to play say over the walls of a room or the like. In this case, the outer end of the pipe 47 may have any of the usual and

approved types of operating tool. As in the previously described construction, this head 45 has spring arms 50 to be engaged by the locking bracket 51, as understood. Also the 5 packing 52 co-operates with the parts to provide an air-tight joint.

Other forms of heads or nozzles may be substituted and are within the contemplation of my invention, and as a further illustration reference is directed to Figs. 6 and 7. In this type of construction the head is designated by the numeral 53, and the same has an enlarged chamber 54 adapted for an operating tool, which in the instance illustrated, consists of a rotatable brush 55, which is adapted to play over the surface to be cleaned. The brush is mounted upon a shaft 56 passing through slots 57 in the ends of the head 53 and through plates 58. These 20 plates are adjustably connected to the head 53, as by thumb screws 60 swiveled to said head 53 and having threaded connection 59 with brackets on the plates 58. This construction permits of the brush to be adjusted 25 vertically relative to the operating surface, by simply rotating the thumb screw 60 in one or the other direction. In order to more firmly hold the brush in its adjusted position, the plates 58 may be provided with 30 slotted ways 61, through which pass screws or the like 62, which in turn engage openings in the head 53. The chamber 54 of the head 53 communicates with the open end of the filtering bag positioned within the 35 vacuum chamber. This head may also be provided with the same parts for engagement with the vacuum chamber, and is preferably also provided with spring arms 63 adapted to be engaged by the locking member 64, as in the previously described constructions, whereby the head is firmly supported in position, and the packing 65 compressed so as to constitute an air-tight joint.

If desired, the same operating means for 45 the pumps may be utilized for driving the rotatable brush 55. In this event a convenient construction of coupling or drive connection may be made, as illustrated in Figs. 6, 7 and 8. In this embodiment of the invention the stub shafts for the pitman rods are given the reference numerals 11' and 12', and a shaft 68 extends in substantial alinement with the stub shafts 11' and 12', the shaft being connected with a crank arm 67, 55 an extension of the shaft 12' as illustrated more particularly in Fig. 8. This shaft 68 projects through the adjacent side wall of the casing and has supported thereon for rotary movement therewith a drive pulley 69. Secured to the shaft 56 of the rotary brush member 60 is a pulley 70. A connecting belt, 71, preferably of spiral wire construction is 70, preferably applied over the said pulleys 69 and 70, whereby as the motor operates the pumps, it at the same time operates the

brush to impart rotation to the latter. It is, of course, obvious that the belt drive 71 may be removed, should it be desired to apply a different construction of head not employing an operating tool, such as a brush. 75

The motor has been described as being preferably an electric one, and the wiring for the latter designated by the numeral 72 passes through an opening in the side of the casing and is secured by suitable clips 73 to the handle parts, and thence is free for connection with the ordinary lamp socket or the like. By this arrangement, it will be seen that the wiring is maintained in position so as not to drag upon the floor or otherwise interfere with the operation of the apparatus. 80

The operation may be described as follows: The wire connections having been coupled up in any suitable manner with the ordinary lamp socket or other electrical supply, the motor is set in operation. The operator grasps the push handle by imparting movement either forward or backward, the apparatus is readily moved through the medium of the supporting wheel 7 over the 90 surface to be cleaned. In normal position the handle is positioned upwardly at an incline, and by exerting downward pressure thereon against the resisting action of the arms 29 the forward edge of the apparatus 95 may be tilted whereby to raise the head or nozzle above the obstructions. When desired to operate under a bed for instance, the arms 29 are swung out of the path of the handle arms 26, when the hand may be lowered to facilitate this operation. The motor has a very firm support upon the main base or bottom 1 of the casing, and is conveniently arranged to the rear of the vacuum chamber and between the opposite side walls 100 105

7. This arrangement not only makes a very substantial support for the motor and parts operatively connected therewith, but also takes up but a minimum amount of space. The motor alternately operates the respective 110 pumps to expand and contract the same, thereby uniformly sucking the air into the chamber through the filtering bag 32 and finally discharging it out of the valve controlled openings 22 in the movable walls 115 of the pumps. The covering 74 constitutes in effect a continuation of the casing forming the dust chamber 5 and motor chamber 6 and conceals the motor, pumps, and the operating connection therewith from view. 120

What I claim is:

1. In an apparatus of the character described, the combination of a vacuum chamber, vacuum creating means, a motor, operative drive connection between the motor 125 and vacuum creating means, a dust inlet nozzle, a rotatable brush carried by the nozzle, means for adjusting the brush vertically relatively to the nozzle, said means including a shaft for the brush mounted in 130

slotted ways in opposite ends of the nozzle, side plates engaging over the ends of the nozzle and secured to said shaft, said plates each having a bracket and an adjusting screw mounted on each end of the nozzle, said screws engaging said brackets to adjustably support the brush in place, and a driving connection between said brush shaft and the motor.

10 2. In a machine of the character described, a casing forming a vacuum chamber, vacuum creating means, a removable dust inlet nozzle, a rotatable brush carried by the nozzle, means for adjusting the brush vertically relative to the nozzle, said means in-

cluding a shaft for the brush mounted in slotted ways in opposite ends of the nozzle, side plates engaging over the ends of the nozzle and secured to said shaft, said plates each having a bracket, and an adjusting screw mounted on each end of the nozzle, said screws engaging said brackets to adjustably support the brush in place. 20

In testimony whereof I affix my signature in presence of two witnesses.

MORRIS S. WRIGHT.
